UNITED STATES PATENT OFFICE.

CLAUDE L. ORR, OF COLUMBUS, OHIO, ASSIGNOR TO THE BUCKEYE STEEL CASTINGS COMPANY, OF COLUMBUS, OHIO.

SIX-WHEEL-TRUCK CONSTRUCTION FOR RAILWAYS.

1,356,653.

Specification of Letters Patent. Patented Oct. 26, 1920.

Application filed March 27, 1920. Serial No. 369,200.

To all whom it may concern:

Be it known that I, CLAUDE L. ORR, a citizen of the United States, and a resident of Columbus, in the county of Franklin and State of Ohio, have invented certain new and useful Improvements in Six-Wheel-Truck Construction for Railways; and I do hereby declare the following to be a full, clear, and exact description of the invention, such as will enable others skilled in the art to which it appertains to make and use the same.

My invention relates to an improvement in six wheel truck construction for railway cars, and is designed particularly as an improvement on the construction disclosed in U. S. Patent No. 1,253,842 granted to Larsen & Johnson January 15th, 1918.

In the patent above referred to two auxiliary bolsters extend transversely of the truck and are supported at their ends in the truck side frames, and two longitudinal bolsters supported at their ends on the transverse bolster carry and support the main bolster extending transversely of the truck.

In this improvement I have provided each of the longitudinal bolsters with an integral right angle arm, the free end of the arm of each longitudinal bolster resting within a recessed seat in the other longitudinal bolster, the two arms forming a support for the main bolster.

In the accompanying drawings; Figure 1 is a view in plan of a truck embodying my invention; Fig. 2 is a view partly in side elevation and partly in section on the line D—D of Fig. 1; Fig. 3 is a view in section on the line A A of Fig. 1; Fig. 4 is a view in section on the line E E of Fig. 1; Fig. 5 is a view in section on the line B B of Fig. 1 and Fig. 6 is a view on the line C C of Fig. 1.

The invention is applicable for use with any six wheel truck, and while I have illustrated one form of side frame in connection with my improvement, I have done so for the purpose of illustration only, and not with the intention of limiting my invention to such, or any particular construction of side frame.

7 represents the truck side frames, there being two to each side with their adjacent ends overlapping, as shown in Fig. 1 for

the connection therewith of the frames 8 carrying the bearing for the center axle 9. Each side frame 7 has a bearing for a journal of an end axle 10, and each is also provided with an opening 11 for the reception of one end of a transverse or auxiliary bolster 12, each bolster 12 being yieldingly supported adjacent its ends, on springs 13 seated within said openings 11. The transverse bolsters 12 are located as shown, one between the front and middle axles, and the other between rear and middle axles, and each is provided on its upper face with two pairs of shoulders 14, shown in Figs. 1 and 6 between which the ends of the longitudinal bolsters 15 rest, the said longitudinal bolsters being supported on the transverse bolsters 12 and provided with depending shoulders 15^a to overhang the transverse bolster and operate to hold the parts in proper position.

Each transverse bolster 12 is depressed at its center as shown in Fig. 6, and as above explained is provided with the upright shoulders 14 which form side supports for the longitudinal bolsters 15 and together with the depending shoulders 15^a on the latter engaging the transverse bolsters 12 operate to retain the parts in the proper relative positions.

Each longitudinal bolster 15 is provided at one side of the center of its length with an integral right angle arm 17, the free end 17^a of which rests within an opening formed in the other longitudinal bolster 15. These arms are depressed at the center as shown in Fig. 5, so that when assembled, the shoulders 17^b on the transverse arms bear against the inner face of the longitudinal bolsters and are held against any longitudinal movement.

The two arms 17 which as above explained are each integral with a longitudinal bolster, are so located that when the parts are assembled the said arms 17 will be in a vertical plane in front of and behind the central axle and equi-distant from the latter.

The main bolster 18 is supported at its ends on the arms 17, the latter having integral flanges 17^c to engage the main bolster at its ends and at its sides adjacent the ends as shown in Figs. 3 and 5, and the main bolster is provided with the laterally projecting lugs 18^a which prevent endwise

movement of the main bolster on the arms 17 or any movement of the arms toward each other.

With this construction the weight of the 5 center bolster and the load thereon will retain the parts in position without any securing devices other than the flange and lugs above referred to.

With high capacity trucks the brake rigging 10 constitutes a very important element of the equipment and requires considerable space for its proper accommodation. With this construction, like that of the patent above referred to I provide for the space 15 by employing longitudinal bolsters which transmit both the side bearing loads and the main or center bolster load to the side frame through transverse bolsters.

It is evident that many slight changes 20 might be resorted to in the relative arrangement of parts shown and described without departing from the spirit and scope of my invention. Hence I would have it understood that I do not wish to confine myself to 25 the exact construction and arrangement of parts shown and described but,

Having fully described my invention what I claim as new and desire to secure by Letters-Patent, is:

- 30 1. In a six wheel truck, the combination of transverse bolsters, two longitudinal bolsters mounted at their ends on the transverse bolsters, each longitudinal bolster having an integral right angle arm the free end of 35 which is supported on the other longitudinal bolster, and a main bolster carried on the right angle arms of the longitudinal bolsters.
2. In a six wheel truck, the combination 40 of two transverse bolsters, two longitudinal bolsters loosely mounted at their ends on the transverse bolsters, transverse parallel connections between the two longitudinal bolsters, and a main bolster loosely supported at its ends on said connections.
- 45 3. In a six wheel truck the combination of

truck side frames, transverse bolsters carried by the latter, two longitudinal bolsters loosely supported at their ends on the transverse bolsters and located adjacent the sides 50 of the truck, transverse members connecting the longitudinal bolsters and located parallel to each other and in planes respectively in front and rear of the center axle, and a main bolster loosely supported at its 55 ends on said transverse members.

4. In a six wheel truck, the combination of truck side frames, transverse bolsters loosely mounted at their ends in openings in said frames, longitudinal bolsters loosely supported on the upper surfaces of the transverse bolsters, parallel transverse members connecting the longitudinal bolsters and a main bolster loosely supported at its ends on the upper surfaces of said transverse 65 parallel members.

5. In a six wheel truck, the combination of truck side frames, transverse bolsters carried at their ends by the latter, longitudinal bolsters supported at their ends on said transverse bolsters each longitudinal bolster having an integral right angle arm the free end of which is supported on the other longitudinal bolster and a main bolster carried on said right angle arms. 75

6. In a six wheel truck, the combination of truck side frames, transverse bolsters carried at their ends by the latter, two longitudinal bolsters supported at their ends by said transverse bolsters, each longitudinal bolster having an integral arm at 80 right angles thereto, the free end of each arm resting within an opening in the other longitudinal bolster, and a main bolster mounted at its ends on said right angle arms. 85

In testimony whereof, I have signed this specification in the presence of two subscribing witnesses.

CLAUDE L. ORR.
